PROTECTOR-ROD FINGER FOR LOOMS

Sherwood O. Dodge, Medford, Mass., assignor to
H. F. Livermore Co., Allston, Mass., a corpora-
tion of Massachusetts

Application October 19, 1933, Serial No. 694,253

6 Claims. (Ch. 139—345)

This invention relates to a protector-rod finger for looms particularly looms of a type having a shuttle box provided with a plurality of cells at either or both ends of the lay.

5 The object of the invention is to provide a protector-rod finger of improved type adapted to engage the shuttle binders in a manner to reduce the frictional resistance therebetween when the boxes are raised and lowered with the result that 10 there is an easier action on both the binders and finger as they move into and out of engagement with each other and the amount of power required to actuate the finger is reduced.

The invention consists in an improved protector-rod finger for the shuttle binders of looms as set forth in the following specification and particularly as pointed out in the claims thereof.

Referring to the drawings:—

Fig. 1 represents a perspective view of a portion of a loom adjacent to an end of the lay and including a portion of a shuttle box in which the shuttles are located with their respective binders positioned thereagainst, a protector-rod finger embodying my invention being illustrated in contact with one of the binders.

Fig. 2 is a side elevation of a protector-rod finger embodying my invention.

Fig. 3 is an elevation of the finger as viewed from the right of Fig. 2.

30 Fig. 4 is a detail transverse section taken on the line 4—4 of Fig. 3.

Fig. 5 is a side elevation of another protector-rod finger embodying my invention.

Fig. 6 is a rear elevation of the protector-rod finger of Fig. 5 viewed from the left of said figure.

35 Fig. 7 is a side elevation of another protector-rod finger embodying my invention.

Fig. 8 is a rear elevation of the protector-rod finger of Fig. 7 viewed from the left of said figure.

40 Like numerals refer to like parts throughout the several views of the drawings.

In the drawings, referring particularly to Figs. 1 to 4 inclusive, 10 represents a lay and 11 represents a group of shuttle cells constituting a shuttle box of well-known form located adjacent to an end portion of said lay. The shuttle cells 11 have shuttles 12 located therein and binders 13 provided therefor adapted to contact with the shuttles 12 when the latter are located within the cells. A protector-rod 14 is mounted in bearings 15 provided therefor on the front of the lay 10. A protector rod finger 16, constituting my invention, is mounted at an end of the rod 14 adjacent to a bearing 15. A spring 17 of well-known form is provided for the rod 14 and acts

to force the protector finger 16 toward the binders 13 for the shuttle cells 11. A dagger 18 of well-known form is rigidly attached to the rod 14.

The finger 16 comprises a body member 19 which is rigidly secured at its lower extremity to the protector rod 14 by means of a set screw 20. The body member 19 has a space 21 provided therein between parallel side portions 22 which are located adjacent to the upper extremity thereof and in this space a roller 23 is mounted to rotate upon a stud 24 which in turn is mounted in both of the side portions 22. The roller 23 embodies therein a rigid bushing 25 constructed of suitable material, preferably metal, around the circumference of which is a flexible peripheral portion 26 preferably constructed of rubber or equivalent material. The rollers 23 engage the edges and front faces of the binders 13 during the upward and downward movements of the shuttle cells 11, the roller 23 being rotated by the various binders during its contact therewith. The rear edges 27 of the side portions 22 of the body member 19 are formed in such a manner that they may engage the edges and front faces of the binders 13 in a manner to actuate the finger 16 in the event that the rollers 23 become worn to such an extent that they do not themselves engage the binders.

The general operation of the protector-rod finger hereinbefore specifically described is as follows:—In the operation of the loom the shuttle boxes are raised and lowered in a well-known manner to correctly position the bottom of each cell 11 with the race plate of the lay in order that the various shuttles 12 will be correctly positioned with respect to said lay. During this upward and downward movement, the roller 23 will engage the surface of the binders 13 with an easy yielding rotating contact, with the result that there will be an easier action on both the binders 40 and fingers as they move into and out of engagement with each other. During the operation of the loom, when a shuttle 12 enters a cell 11 properly, the protector finger 16 will be pushed forwardly and the dagger 18 will be lowered, so that 45 it will not be brought into operative engagement with certain instrumentalities not illustrated in the drawings, but well known to those skilled in the art, and which are adapted to operate a shipper handle for starting and stopping the loom. If, however, the shuttle does not enter the cell, the spring 17 will keep the roll 23 of the protector finger 16 pressed against the binder and the dagger 18 will remain in a raised position so that as the lay moves forward it will engage the mechanism 50 55

for operating the shipper handle and the loom will be stopped.

In Figs. 5 and 6 I have illustrated a modified embodiment of my invention in which 28 represents a finger comprising a body member 29 which is adapted to be fastened to a protector rod 14. Mounted upon the body member 29 at an intermediate point thereon and extending upwardly therefrom is an arm 30 which is pivotally secured 10 to said body member by means of a pin 31. Mounted between side portions 32 of the arm 31 is a roller 33 which is rotatably mounted upon a stud 34 in turn mounted in the side portions 32. A spring 35 is secured to the body member 29 and 15 engages the upper portion of the arm 30 in a manner to normally hold said arm against an abutment 36 provided upon the body member 29. A screw 37 is provided at the upper extremity of the body member 29 and constitutes an adjustable 20 stop to limit the yielding movement of the arm 30 toward the body member 29. In this embodiment of the invention, the roller 33 is preferably constructed of metal, although it may be constructed of rubber if it is so desired.

In Figs. 7 and 8 still another modified embodiment of the invention is illustrated in which 38 represents a protector finger having a body member 39 embodied therein. An arm 40 is pivotally secured to the upper extremity of the body member 39 by means of a pin 41 and said arm hangs 25 downwardly beside the body member and swings upon said pin. Mounted between side portions 42 of the arm 40 is a roller 43 which is rotatably mounted upon a stud 44 in turn mounted in the side portions 42 of the arm 40. A coil spring 45 is interposed between the body member 39 and lower portion of the arm 40 and acts to normally hold the lower portion of said arm against an abutment 46 provided upon the body member 39.

In this embodiment of the invention the roller 43 is preferably constructed of metal, but may be constructed of rubber if it is so desired.

Each of the fingers 28 or 38 illustrated in Figs. 5 to 8 inclusive may be attached to the protector rod 14 in lieu of the finger 16 if it is so desired, in which event the rollers will function to reduce the frictional resistance between the binders and the fingers.

I claim:

50. 1. A protector-rod finger for shuttle binders comprising, in combination, a body member, an

arm pivotally attached to said body member to yield relatively thereto, and a roller mounted upon said arm and adapted to yieldingly engage said binders.

2. A protector-rod finger for shuttle binders comprising, in combination, a body member, an arm pivotally attached thereto, a roller mounted upon said arm, and a spring interposed between the arm and body member and adapted to hold the roller in yielding engagement with said binders. 5

3. A protector-rod finger for shuttle binders comprising, in combination, a body member, an arm pivotally attached thereto at an intermediate point thereon and projecting upwardly therefrom, a roller mounted upon said arm, a spring interposed between the arm and body member and adapted to hold said roller in yielding engagement with said binders, and adjustable means to limit the yielding movement of said arm. 15

4. A protector-rod finger for shuttle binders comprising, in combination, a body member, an arm pivotally attached thereto at an intermediate point thereon and projecting upwardly therefrom, a roller mounted upon said arm, a spring interposed between the arm and body member and adapted to hold said roller in yielding engagement with said binders, and adjustable means to limit the yielding movement of said arm, said arm having a surface embodied therein also adapted to engage the binders in the event of excessive reduction of the diameter of the roller. 20

5. A protector-rod finger for shuttle binders comprising, in combination, a body member, an arm pivotally attached thereto at the upper end 35 thereof and hanging downwardly from said pivot, a roller mounted upon said arm, and a spring interposed between the arm and body member and adapted to hold the roller in yielding engagement with said binder. 40

6. A protector-rod finger for the binders of a vertically shiftable shuttle box comprising, in combination, a body member, a horizontal axis member mounted thereon, and a roller carried by said axis member and yieldable relatively to said body member whereby said roller may have yielding rotative engagement with said binders during the shifting movement independent of any yielding action of the body member. 45:

SHERWOOD O. DODGE. 50:
